Primary Examiner—Janice E. Seeger(74) *Attorney, Agent, or Firm*—Jones, Day, Reavis & Pogue**(57) CLAIM**

The ornamental design for a table base, as shown and described.

DESCRIPTION

FIG. 1 is a side perspective view of a table base showing our new design, the opposite side view being a mirror image thereof;

FIG. 2 is another side perspective view, the opposite side perspective view being a mirror image thereof; and,

FIG. 3 is a top plan view thereof.

The bottom of the table base is plain and unornamented.
